UNITED STATES PATENT OFFICE

ALBERT C. ACKERMAN, OF JEANNETTE, PENNSYLVANIA

WINDMILL WHEEL

Application filed September 3, 1927. Serial No. 217,473.

This invention relates to a windmill wheel, the general object of the invention being to provide a wheel with pivoted blades or vanes and governor means for adjusting the pitch of the blades or vanes so as to control the speed of the wheel.

Another object of the invention is to provide manually operated means which are associated with the governor means for placing the blades edgewise to the wind when it is desired to stop the rotation of the wheel.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a rear view of the improved wheel.

Figure 2 is a section on line 2—2 of Figure 1.

Figure 3 is a detail sectional view through a portion of the shaft and the collars thereon.

Figure 4 is a section on line 4—4 of Figure 3.

Figure 5 is a section on line 5—5 of Figure 3.

Figure 6 is an edge view showing one of the pivots of one of the blades.

Figure 7 is a section on line 7—7 of Figure 2.

In these views, 1 indicates the shaft of the windmill which carries the wheel and 2 indicates the hub of the wheel which is fastened to the shaft. The spokes 3 of the wheel are fastened to the inner ring 4 and the outer ring 5, these rings supporting the blades or vanes 6. These vanes are preferably of the shape shown and a pivot 7 is arranged at each end of each blade, the outer pivots engaging the outer ring and the inner pivots the inner ring. The rear edge of each blade has a number of ears 8 thereon and links 9 are pivotally connected with these ears, each link

connecting a blade with an adjacent blade so that the blades must move in unison. Some of the pivotal pins of the links are extended inwardly as shown at 10, and the inner ends of these pins have rounded heads. The drawings show two of these pins as being extended.

A ring 11 is connected by the spokes 12 with the rear part of the hub and upper and lower governor arms 13 are pivoted intermediate their ends to this ring. The two arms

are connected together by the links 14 and a projection 15 extends outwardly from each arm and has a rounded outer end and a link

16, having a socket at each end, connects each projection 15 with the extension pin 10, the sockets of the links engaging the rounded ends of the pins and projections so that the movement of the governor arms will be communicated to the blades. The governor arms

carry the usual weights 17 and a coil spring 18 has one end connected with each arm and its other end to a projection 19 on the ring 11, the latter connection being an adjustable one so that the tension of the spring can be regulated.

A collar 20 is fastened to the shaft 1 and a grooved collar 21 is keyed to the shaft so that it has sliding movement thereon but is held against rotary movement. A coil spring 22 on the shaft abuts the collar 21 and a collar

23 fastened to the shaft and tends to hold the collar 21 against the collar 20. L-shaped arms 24 are pivoted to the collar 21 and have their short portions extending over the short ends of the governor arms. Slotted links 25

are pivoted to the collar 20 and a pin 26 on each arm 24 carries a roller 27 which engages the slot in each link 25. Thus when the collar 21 is moved toward the collar 23, it will contract the spring 22 and the links

25 will cause the arms 24 to move toward each other, and in this movement, the arms will engage the governor arms and move them outwardly against the action of the springs

18 and in the same manner that the weights 17 would move the governor arms under the action of centrifugal force and this outward movement of the governor arms will be communicated to the blades through means of

the projections 15, the links 16 and the ex-

tended pins 10, so that the blades will be rocked on their pivots and in this manner the resistance the blades offer to the wind can be adjusted, which will control the speed of the wheel. When the blades are moved to an extent which will place them edgewise to the wind, the wheel will come to rest, as will be understood.

A bell crank 28 is pivoted to a part of the windmill and has one end engaging the groove in the collar 21 and its other end is attached to a cable 29 so that a person standing on the ground can adjust the collar to regulate the speed of the wheel as before described or to entirely stop the wheel by moving the blades to a position where they will extend edgewise to the wind.

From the foregoing it will be seen that I have provided governor means which are adjustable for regulating the speed of the wheel according to the strength of the wind by adjusting the vanes of the wheel and also manually operated means for controlling the speed or for stopping the wheel.

It will, of course, be understood that the parts may be enclosed in a suitable casing or housing, if desired or necessary.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A windmill wheel comprising a hub, spokes connected therewith, inner and outer concentric rings carried by the spokes, blades having their ends pivotally supported between said rings, means for connecting the blades together so that they will move in unison, a small ring carried by the hub and arranged wholly to one side of the wheel, a governor connected with said small ring and comprising a pair of arms pivotally supported intermediate their ends, weights on said arms, springs for yieldingly holding the arms against movement, means for connecting the arms with the blades, means for setting the governor for predetermined speeds of said wheel, a collar slidably mounted on the shaft of the wheel, arms pivotally connected with the collar and having portions engaging the arms of the governor, slotted arms connected with the shaft and having their slotted portions engaging the parts on the arms carried by the collar, and means for moving the collar so that the slotted arms will cause the arms on the collar to press the arms of the governor inwardly for the purpose specified.

2. A windmill wheel comprising a hub, spokes connected therewith, inner and outer rings carried by the spokes, blades having

their ends pivotally supported by the rings, ears on the rear edges of the blades adjacent their inner ends, links connecting the blades together, each end of each link extending between a pair of ears, pivot pins pivotally connecting the links with the ears, some of the pins being extended inwardly toward the hub, a small ring connected with the hub and wholly arranged at one side of the wheel, a pair of governor arms pivotally connected intermediate their ends to said small ring, a weight on one end of each arm, a spring connecting the weighted part of each arm to the small ring, links connecting the arms together, an outwardly extending projection on each arm, and a link connecting each projection with the extended part of said pivot pin.

3. A windmill wheel comprising a hub, spokes connected therewith, inner and outer rings carried by the spokes, blades having their ends pivotally supported by the rings, ears on the rear edges of the blades adjacent their inner ends, links connecting the blades together, each end of each link extending between a pair of ears, pivot pins pivotally connecting the links with the ears, some of the pins being extended inwardly toward the hub, a small ring connected with the hub and wholly arranged at one side of the wheel, a pair of governor arms pivotally connected intermediate their ends to said small ring, a weight on one end of each arm, a spring connecting the weighted part of each arm to the small ring, links connecting the arms together, an outwardly extending projection on each arm, a link connecting each projection with the extended part of said pivot pin, and means for setting the governor for predetermined speeds of said wheel.

In testimony whereof I affix my signature.

ALBERT C. ACKERMAN.
